UNITED STATES PATENT OFFICE.

HOWARD TERHUNE, OF MASSILLON, OHIO.

DROP HAMMER.

Application filed July 22, 1921. Serial No. 486,747.

To all whom it may concern:

Be it known that I, HOWARD TERHUNE, a citizen of the United States, residing at Massillon, in the county of Stark and State 5 of Ohio, have invented new and useful Improvements in Drop Hammers, of which the following is a specification.

The invention relates to the construction of drop hammers, and the improvements pertain to the lateral adjustment of the upright members of the frame and to the construction and operation of the releasing lever mechanism for the friction rolls.

The adjustment of the lower ends only of 15 an upright frame member necessarily inclines the same and requires frequent replanning of the upright guides; to avoid which the present improvement involves means for adjusting the upper ends as well 20 as the lower ends of the upright members, and also includes improved means for adjusting the uprights upon the base or anvil member, to prevent a twisting or turning of the upright thereon.

25 A rigid clamping of the friction roll releasing lever to the frame of the machine and to the friction bar, requires a tighter adjustment than normally necessary of the friction rolls, to properly respond to the varying 30 shocks of the hammer in different kinds of work, and the usual connections of this lever tends to turn its bracket on the friction bar; to avoid which the present invention involves the use of yielding means for 35 mounting the releasing lever, with a limiting stop for the same, and a sliding guide to prevent a turning of the lever bracket on the friction bar.

40 A knock-off lever secured to the friction bar also tends to turn the bar; to avoid which the present improvement involves a sliding knock-off lever carried by links swinging on a bracket adjustably secured to an upright member of the frame.

45 Preferred forms of the several improvements embodied in a board drop hammer, are illustrated in the accompanying drawings, forming part hereof, in which—

Figure 1 is a front elevation of the entire 50 machine;

Fig. 2, a right side elevation of the same;

Fig. 3, a left view elevation section of the same on the median line III—III;

Fig. 4, a fragmentary front view elevation section on line IV—IV, Figs. 2 and 3. 55

Fig. 5, a fragmentary plan section on line V—V, Fig. 4;

Fig. 6, an inner end view of the upright frame adjusting head;

Fig. 7, a fragmentary front elevation section of the frame base, and left upright as on line VII—VII, Figs. 2 and 3;

Fig. 8, a plan section of the left upright and base on line VIII—VIII, Fig. 7;

Fig. 9, a detached perspective view of one 65 adjusting leg;

Fig. 10, a detached perspective view of one wearing plate;

Fig. 11, a fragmentary front elevation, partly in section of the releasing lever, the 70 section being on line XI—XI, Fig. 13;

Fig. 12, a right view section of the releasing lever mechanism on line XII—XII, Fig. 11;

Fig. 13, a plan section of the releasing 75 lever mechanism on line XIII—XIII, Fig. 11;

Fig. 14, a reduced right side elevation of the releasing lever bracket showing the lever 80 in section;

Fig. 15, a plan view of the knock-out mechanism showing the frame upright in section on line XV—XV, Fig. 1;

Fig. 16, a front elevation section of the knock-off mechanism on line XVI—XVI, 85 Fig. 15;

Similar numerals refer to similar parts throughout the drawings.

Upon the base or anvil 1 of the machine, are mounted the upright members 2 and 2', 90 upon which is secured the housing 3, in which are mounted the bearings 4 carrying the shafts 5 for the friction rolls 6 in well known manner.

95 On each side of the base or anvil 1 is provided a bearing for the respective upright members 2 and 2' of the frame, each bearing having an inner portion 7 in a lower plane and an upper portion 7' in an upper plane, and a wedge shoulder 8 at the junction 100 of the inner and outer portions of the bearing.

The foot of each upright member is formed with an inner bearing portion 9 in a lower plane and an outer bearing portion 9' in 105 an upper plane adapted to rest and slide

laterally upon the corresponding bearing portions of the base; and in each foot is also formed a wedge shoulder 10 spaced from and opposing the wedge shoulder 8 on 5 the base.

One of the wedge shoulders, preferably the base shoulder, is located at an endwise angle from the normal plane of the other shoulder, thereby forming a tapered channel 10 between the shoulders in which is entered a tapered wedge 11 having its thinner end directed rearward in one side and forward in the other side, by which the uprights may be adjusted upon the base of the 15 frame, the wedge being moved and held endwise by the screw stem 12 secured to the frame and the lock nuts 13 thereon.

Transverse guide channels 15 and 15' are provided in the respective bearings of the 20 base, preferably in the median line thereof, and corresponding transverse guide tongues 16 and 16' depend from the foot bearing portions of the uprights. The guide tongues are fitted to the channels so as to guide the 25 lateral adjusting movements of the upright on the base and hold the V-guides 17 on their inner sides in true alinement with each other.

The location of the wedge shoulder 8 in each side of the base, intermediate the respective bearing portions thereof, and the 30 location of transverse guide grooves outside, as well as inside, of the adjusting wedge and co-operating shoulders, serves to positively hold the uprights in true position on the 35 base and prevent any turning or twisting thereof during an adjustment of the uprights or the operation of the machine.

For adjusting the uprights upon the base, the clamping bolts 18 and 18' are loosened 40 and one of the uprights, preferably on the right side of the machine as illustrated, is properly adjusted by the corresponding wedge; after which the other side is adjusted inward by the corresponding wedge, and the 45 clamping bolts are then tightened to hold the uprights in their adjusted position.

The housing 3 is secured on the upper ends of the uprights 2 and 2' by a pair of clamping bolts 19 one in front and one in rear, extending transversely through the upper ends 50 of the uprights. The bottom 20 of the housing bears at each side upon the seats 21 formed on the tops of the uprights, inside of which a flange 22 depends from the housing 55 upon which are formed hubs 23 and 23' through which the bolts 19 are passed. The hub 23 on one is normally in abutment with the inner face of the corresponding upright.

An adjusting screw sleeve 24 is provided 60 on each rod 19 in a screw socket 25 formed in the other upright; and upon the inner end of the screw sleeve is provided an adjusting head 26 having radial lugs 27 on its face engaging in corresponding channels 27' in the 65 outer end of the hub 23'.

Washers 28 are preferably provided on each end of the bolt 19 for bearing squarely against the outer sides of the uprights; outside of which washers are located the spiral springs 29 against which nuts 30 are screwed 70 upon the ends of the bolts, for clamping and securing the parts in position.

By this construction and arrangement, it is evident that the uprights may be adjusted to and from each other by an adjustment of 75 the screw sleeve 24 in the one upright; the same being done by the first releasing of nuts 30, on the bolts 19 and sliding the upright 2' outward to disengage the adjusting head lugs 27 from the hub channels 28; after 80 which the screw sleeve is turned sufficiently to give the desired adjustment, and the shifted upright is moved back into position, and the parts clamped together by the nuts 30.

By thus adjusting the upper ends, as well as the lower ends of the uprights, it is evident that they may always be maintained with their V-guides 17 in true parallel relation, thereby avoiding the necessity of a frequent planing of the guides to keep them 90 true to each other.

The hammer head 31 operates between the guides 17 and is normally sustained in upper position by means of the board 32 and the 95 clamping jaws 33 mounted in the housing, one jaw being locked in clamping position by a clamp rod 34, and the other jaw being released from and returned to clamping position by the clamp rod 34', the rock lever 100 35, connecting bar 36 and the pedal 37 in well known manner.

The hammer head is raised to upper position by means of the friction rolls 6 eccentrically mounted in the head, one roll being 105 located in contacting position by a friction bar 38 and the other roll being released from and engaged with the board by a friction bar 38'; the foot 39 of the latter bar normally resting in releasing relation upon a 110 step 40, secured to the base in well known manner.

The improved roll releasing lever mechanism includes a bracket 41 secured at its forward end by the clamping jaws 42 and the 115 bolts 43 to the friction rod 38', and having a runner 44 on the outer side of its rear end in sliding contact with the inner side of the abutment block 45 adjustably secured by a bolt 45' to the face of the upright 2.

The releasing lever 46 extends through the bracket 41 and is horizontally pivoted on the pin 47 secured in the bracket. The free end of the lever extends inward in front of the hammer, and in the path of the hammer pin 48, by means of which it is actuated when the hammer rises to upper position.

The outer end of the releasing lever is pivoted on a pin 49 carried by a bearing 50 on the lower end of a stem 51, yieldingly sup-

ported by a bracket 52 adjustably secured to the upright 2 by a bolt 53. The bracket 52 is provided with a bearing cup 54 having a washer ring 55 in its bottom upon which 5 rests a coil spring 56 located around stem 51, which extends upward freely through an aperture 57 in the bottom of the cup, and has a stop head 58 on its upper end resting on the spring and adjusted by a nut 59. The 10 bottom of the stop head is spherically convexed for bearing on a correspondingly concaved seat 60 formed in the rim of the bearing cup.

By these means, the pivotal bearing 50 for 15 the outer end of the roll release lever 46 is yieldingly supported by the spring in the bearing cup, until the load upon the bearing carries the stop head downward to its seat on the cup; and upon a withdrawal of the 20 load, the spring re-acts to raise the bearing 50 into normal yielding position. The abutment of the upper end 61 of the bearing 50 against the bottom of the bearing cup, serves to stop a further upward movement of the 25 pivotal bearing.

The yielding pivotal bearing thus provided for the roll releasing lever 46, absorbs and relieves the first shock when the hammer head pin 48 impinges the lever, and the friction rod is lifted to release the rolls from the friction board. After the hammer head comes to rest in upper position, the spring re-acts to lift the friction bar up on to its seat before the board begins to drop; there- 35 by reducing the degree of the frictional adjustment of the roll which would otherwise be necessary, to accommodate the excessive shocks of the hammer caused by varying kinds of work.

40 The sliding bearing of the runner 43 against the abutment block 44 when the hammer head pin 48 impinges the releasing lever 46, prevents any turning of the lever bracket 41 upon the friction bar 38'; the slight 45 swinging of the bar to and from the step 40 being accommodated by the movement of the stem 51 in the slotted aperture 57 in the bottom of the bearing cup, and the swinging of the same on the universal joint formed by 50 the head 58 and a spherical seat 60.

The improved knock-off lever mechanism includes a bracket 62 adjustably secured to the upright 2 by bolts 63, a transverse rock lever 64 carried by a pivot bolt 65 in the forward end of the bracket having the knock-off lever 66, pivoted on the inner end, and a spring bolt 67 pivoted on the outer end with a link 68 connecting the lever with an intermediate portion of the bracket.

60 The knock-off lever 66 is pivoted on a bushing 69 through which the friction bar 38' freely passes for sliding upward and downward, and for such turning as may be required in its movements; and when the 65 hammer drops and impinges the knock-off

lever, the same moves bodily forward, by swinging on the pivotal link and arm, and pushes the friction rod forward off the step 40, and the rod then drops down upon the lower step 40' by sliding through the pivotal bushing and without any turning of the rod.

I claim:

1. A drop hammer frame including a base and an upright, a bearing on the base having 75 a wedge shoulder intermediate its sides, a corresponding bearing and an opposing shoulder on the foot of the upright, and a wedge co-operating with the shoulders for adjusting the upright.

2. A drop hammer frame including a base and an upright, a bearing on the base having a wedge shoulder intermediate its sides, a corresponding bearing and an opposing shoulder on the foot of the upright, and a 85 wedge co-operating with the shoulders for adjusting the upright, there being guide channels in one bearing and guide tongues in the other bearing extending both ways from the wedge shoulders.

3. A drop hammer frame including a base and an upright, a bearing on the base having lateral portions in different planes and an intervening wedge shoulder, a corresponding bearing and opposing shoulders on the 95 foot of the upright, and a wedge co-operating with the shoulder for adjusting the upright.

4. A drop hammer frame including a base and an upright, a bearing on the base having 100 lateral portions in different planes and an intervening wedge shoulder, a corresponding bearing and opposing shoulders on the foot of the upright, and a wedge co-operating with the shoulder for adjusting the upright, there being guide channels in one bearing and guide tongues in the other extending both ways from the wedge shoulders.

5. A drop hammer frame including a base 110 with uprights thereon and a housing on the uprights, at least one of the uprights being laterally adjustable on the base, and means for adjusting the upper end of the same upright including bearings on the uprights for 115 the sides of the housing, hubs on the housing depending inside the uprights, a transverse clamping bolt extending through the uprights and the hubs, and adjusting means between one hub and the adjacent upright.

6. A friction roll releasing mechanism for the friction rod of a board drop hammer, including a bracket on the friction rod and a bracket on the hammer frame, a releasing lever having a pivotal bearing in each 125 bracket, one or more bearings having yielding supports, and means on the hammer for actuating the lever.

7. A friction roll releasing mechanism for the friction rod of a board drop hammer, in- 130

cluding a bracket on the friction rod and a bracket on the hammer frame, a releasing lever having a pivotal bearing in each bracket, one of the bearings having yielding supports, means for stopping the yielding support, and means on the hammer for actuating the lever.

8. A friction roll releasing mechanism for the friction rod of a board drop hammer, including a bracket on the friction rod and a bracket on the hammer frame, a releasing lever having a pivotal bearing in each bracket, means on the hammer for actuating

the lever, a slide runner on the rod bracket, and an abutment block on the frame to stop 15 a turning of the rod bracket.

9. Kick off mechanism for the friction rod of a board drop hammer including a bracket on the hammer frame, a rock arm and a link pivoted on the bracket, a kick off arm pivotally connected to the rock arm and the link, the former connection including a bushing freely surrounding the friction bar, and means on the hammer for actuating the kick off lever.

HOWARD TERHUNE.
